Livingston, Roggen & Adams.

Latch.

No. 88.

Patented June 5, 1849.

No. 88.—*Improved Knob or Left Hand Lock.*
What we claim as our invention and desire to secure by additional letters patent, is the constructing the lock tumblers of two parts C, C, of such a form and combined with each other and with the arms b, b, of the lock bolt, in such a manner as relation to the key holes F, F, placed in reversed positions near each end of the lock, that a key will operate the tumbler and bolt equally well when inserted into either of the said key holes, substantially in the manner herein set forth.
